United States Patent Office.

GEORGE B. OWEN, OF WINSTED, CONNECTICUT.

Design No. 3,815, dated January 11, 1870.

DESIGN FOR A CLOCK-FRAME.

The Schedule referred to in these Letters Patent and making part of the same.

To all whom it may concern:

Be it known that I, GEORGE B. OWEN, of Winsted, in the county of Litchfield, and State of Connecticut, have invented a new and improved Design for a Frame for Clock-Works; and I do hereby declare that the following is a full, clear, and exact description thereof, which will enable others skilled in the art to make and use the same, reference being had to the accompanying drawing, forming part of this specification, in which the figure is a front view of a frame for clock-works, illustrating my improved design.

My invention has for its object to furnish, and con-

sists in an improved design for a frame for clock-works, as hereinafter more fully set forth.

The nature of my design is fully represented in the accompanying drawing, to which reference is made.

Having thus described my invention,

I claim as new, and desire to secure by Letters Patent—

The design for a frame for clock-works, as shown.

GEO. B. OWEN.
